(57) **CLAIM**

We claim the ornamental design for a side-by-side shotgun arcade controller, as shown and described.

DESCRIPTION

FIG. 1 is a side view of a side-by-side shotgun arcade controller;

FIG. 2 is a side view thereof showing the side opposite that shown in FIG. 1;

FIG. 3 is a top view thereof;

FIG. 4 is a bottom view thereof;

FIG. 5 is rear view thereof;

FIG. 6 is a front view thereof; and,

FIG. 7 is a perspective view thereof.

The broken lines are for the purposes of illustrating portions of the side-by-side shotgun arcade controller that form no part of the claim.
